UNITED STATES PATENT OFFICE

ALEXANDER McNAB, OF BRIDGEPORT, CONNECTICUT

BOILER CIRCULATOR

Application filed August 13, 1930. Serial No. 474,923.

This invention relates to new and useful improvements in boiler circulators and particularly relates to improvements on the boiler circulator shown in my prior Patent 5 1,155,832 of October 5, 1915.

The primary object of the present invention is to provide a circulator whereby the water in a boiler will be compelled to travel in a certain path or in certain paths, resulting in the water throughout the boiler having a substantially constant temperature and further resulting in all of the water in the boiler being in circulation preventing the formation of scale.

15 A further object of the invention is to provide a circulator of simple construction and which may be easily and quickly installed in a boiler and which may be easily and quickly released for movement along the 20 boiler tubes to permit of inspection and repair, the operating position of the circulator being at the ends of the tubes adjacent the front wall of the combustion chamber.

Other objects and advantages will become 25 apparent from a consideration of the following detailed description taken in connection with the accompanying drawings showing one embodiment of the invention. However, it is to be understood that the invention is not limited to the details shown and described since changes in the construction and arrangement of parts may be made without departing from the spirit of the 30 invention or the scope of the appended 35 claims.

In the drawings:—

Figure 1 is a section on the line 1—1 of Fig. 2;

40 Fig. 2 is a section on the line 2—2 of Fig. 1;

Fig. 3 is an enlarged detail view showing the veins and the deflector nozzles at the top of the fire tubes, the side plates being shown in place;

45 Fig. 4 is a similar view taken at the bottom of the fire tubes;

Fig. 5 is a top plan view of the parts shown in Fig. 4; and

50 Fig. 6 is a perspective view of the circulator detached.

Referring in detail to the drawings, at 10 is shown the boiler shell or casing within which is enclosed a plurality of fire boxes or chambers 11 and a plurality of sets or series of fire tubes 12, 13, 14 and 15 there being 55 one series of fire tubes for each fire box 11. Rearwardly within the shell or casing 10 is the combustion chamber 16 connected with the fire boxes and the tubes of the various sets or series.

50 My improved circulator is applied to the fire tubes and the circulator is exactly the same as applied to sets of tubes 12 and 15 but is somewhat enlarged as applied to tubes 13 and 14 since but one circulator is applied 60 to both sets of tubes.

55 As applied to the sets of tubes 12 and 15, the circulator includes a pair of vertically disposed plates 17 and 18, one being arranged at each of the outer sides of the sets of tubes and the plates extending above and below the tubes and at their lower ends curving outwardly as at 19 receiving the 65 upper portions of the fire boxes between them. The plates 17 and 18 are not of very great width but extend forwardly along the outer sides of the fire tubes from the front wall of the combustion chamber.

70 Plates 17 and 18 are secured in place by 75 means of hooked bolts 20 and nuts 21 for such bolts. The bolts hook over the tubes and as the nuts are tightened the plates are drawn into position against the tubes. Between the upper ends of the plates, which as stated project above the fire tubes, there are secured transverse plates 22 and 23, the plates 22 and 23 being bolted, riveted or otherwise secured to the upper ends of the plates 17 and 18.

80 As clearly shown the transverse plates or vanes 22 are of less height than the vanes or blades 23 and the blades 23 include forwardly projecting horizontal portions 24. The space 25 between the horizontal portions 24, constitutes a nozzle, and owing to the 85 position of the plate 22 beneath the lowermost horizontal portion 24, a nozzle will be formed beneath such portion. This nozzle arrangement is such that heated water rising or boiling up through the fire tubes is 90 95 100

directed or deflected forwardly toward the front of the boiler.

Beneath the fire tubes and secured to the side plates 17 and 18 there are deflecting blades or vanes 26, the same being secured to the side plates by having their end portions bent over and bolted, riveted or otherwise secured to the side plates. These lower blades 26 are shown as four in number the same as the upper blades, but it will be understood that the number may be varied. Attention is called to the fact that the lower blades adjacent the combustion chamber are arranged somewhat more close together than are the blades remote from the combustion chamber.

The circulator for the two central sets of tubes 13 and 14 is much the same as the circulators for the sets of tubes 12 and 15. This larger circulator includes side plates 27 and 28 similar to the plates 17 and 18 except that they are somewhat longer since more tubes are used and these plates 27 and 28 at their lower ends curve outwardly as at 29 so as to include the upper portions of two fire boxes between them. The plates are secured to the fire tubes as by hooked bolts 20 and nuts 21 and at their upper ends carry the plates 22 and 23, the plates being the same as the corresponding plates previously described in connection with the circulators for the sets of tubes 12 and 15. Between the lower ends of the plates 27 and 28 are secured the transverse plates or vanes 26.

A curved deflector plate 30 extends across the boiler in the rear of the combustion chamber 16 and is secured to the boiler as by rivets 31 and to the braces 32 of the boiler as by hooked bolts 33. At the front of the boiler is a deflector 34 similar to the deflector 30 and resting at its lower edge on the upper fire tubes while at its upper edge it is secured to the braces 32 as by means of hooked bolts 35.

While it is believed that the operation will be apparent it is desired to point out that water ascending due to heat transmitted to it from the fire chambers or boxes will be the hottest adjacent the combustion chamber 16 and that as the water rises owing to being heated it will engage the plates 26 and be deflected rearwardly into engagement with the front wall of the combustion chamber. It is well known that the combustion chamber tube plate is directly exposed to the full force of the flame and gases in the combustion chamber, and is, therefore, one of the hottest surfaces in the boiler. However, owing to the necessity of having to install the tube plate in a vertical position, within the boiler, it cannot be considered a heating surface, for the reason that all steam containing bubbles following the line of least resistance ascend directly against this over heated tube plate insulating it from direct

contact with the water contained within the boiler. With my arrangement the water is directed against the tube plate washing the bubbles away from the same and breaking up this insulating action described.

Further, the boiling water bubbling upwardly through the fire tubes is confined between the plates 17 and 18 and 27 and 28 as the case may be, these plates serving to maintain the water in a definite channel. On reaching the top of the fire tubes the water engages the plates 22 and 23 and is deflected forwardly whereby it is prevented from bubbling up into the steam space and resulting in wet steam. The water being directed forwardly by the nozzles will descend at the forward portion of the boiler as other water is ascending rearwardly in the boiler whereby continuous circulation is set up.

It will be noted that side plates 17, 18 or 27, 28 will confine the water as it moves upwardly from the fire chambers and prevent it from spreading laterally through the tubes. In other words once the water enters between the plates, having passed through the vanes 26 it cannot escape laterally through the tubes or between the tubes but must move upwardly and pass out between the plates or vanes 22 and 23. Thus a definite channel for the water to pass through is created. Further, as the water passes outwardly through the upper vanes 22, 23 it will create a circulation through the passageways or spaces between or at the sides of the plates. For example, the water being directed forwardly by the nozzles will draw water upwardly through the space between the plates 18 and 27 and the space between the plates 28 and 17.

Having thus described my invention, what is claimed is:

1. In a boiler circulator, a pair of spaced side plates extending above the fire tubes of the boiler, and blades extending between and rigidly connected at their ends to the extending portions of the side plates above the fire tubes, said blades inclining forwardly of the boiler.

2. In a boiler circulator for a horizontal fire tube boiler, a pair of vertically disposed plates arranged one at each side of the fire tubes and extending above the fire tubes, and blades supported between the extending end portions of the side plates above the fire tubes, said blades inclining forwardly of the boiler.

3. In a boiler circulator for a horizontal fire tube boiler, a pair of vertically disposed plates arranged one at each side of the fire tubes adjacent the combustion chamber tube plate, said vertical side plates extending above the fire tubes, and a blade rigidly secured at one end of the upper extending portion of one of said plates and projecting in the direction of the extending portion

of the other of said plates and across said tubes, said blade inclining forwardly of the boiler.

4. In a boiler circulator for a horizontal fire tube boiler, a pair of spaced side plates extending above the fire tubes of the boiler, and blades supported between the end portions of the plates above the fire tubes, said blades formed at their upper portions into horizontally extending nozzles.

5. In a boiler circulator, a pair of spaced side plates extending below the fire tubes of the boiler, and a series of blades supported between the end portions of the side plates below the fire tubes, said blades inclining rearwardly of the boiler.

6. In a boiler circulator, a pair of spaced side plates extending below the fire tubes of the boiler, said plates at their lower ends curving away from each other whereby their lower end portions are disposed laterally of the boiler fire box, and a series of blades supported between the end portions of the side plates below the fire tubes and above the fire box.

7. In a boiler circulator, a pair of spaced side plates extending above and below the fire tubes of the boiler, and two series of spaced water deflecting blades arranged respectively above and below the fire tubes and between the end portions of the plates.

8. In a boiler circulator, a pair of spaced side plates extending above and below the fire tubes of the boiler, and two series of spaced water deflecting blades arranged respectively above and below the fire tubes and between the end portions of the plates, some of said blades above the fire tubes including horizontally extending portions forming a nozzle.

9. In a boiler circulator for a horizontal fire tube boiler, a pair of spaced plates arranged one at each side of a set of boiler tubes, said plates extending above the tubes of said set, and blades supported between the end portions of the plates above the fire tubes, said blades inclining forwardly of the boiler.

Signed at Bridgeport, in the county of Fairfield, and State of Connecticut, this 30th day of July, A. D. 1930.

ALEXANDER McNAB.
